ATTORNEY

UNITED STATES PATENT OFFICE.

NIC KRUMP, OF CHICAGO, ILLINOIS.

BENDING BRAKE.

Application filed December 23, 1922. Serial No. 608,639.

To all whom it may concern:

Be it known that I, NIC KRUMP, a citizen of the United States, and a resident of Chicago, in the county of Cook and State 5 of Illinois, have invented certain new and useful Improvements in Bending Brakes, of which the following, when taken in connection with the drawings accompanying and forming a part hereof, is a full and complete specification.

This invention relates to bending brakes by means of which sheet metal of large size and of considerable thickness may be bent or folded.

15 Among the objects of the invention are to obtain a brake of great strength and rigidity; which is durable and not liable to break or get out of order; which is economically made; and which is easily understood 20 and operated by men skilled in the art of bending sheet and bar metal.

In the drawings referred to—

Fig. 1 is a front elevation of a bending brake.

25 Fig. 2 is an end elevation; and

Fig. 3 is a vertical section on line 3—3 of Fig. 1, viewed as indicated by arrows.

A reference character applied to designate a given part indicates said part throughout 30 the several figures of the drawings wherever the same appears.

A, A', and B, B' represent the standards or legs of the brake; a, a, represent diagonally extending braces, and b, b, base members. Said legs, braces and base members 35 are rigidly secured together by rivets C, C.

The bed of the brake is supported by the frame formed by the standards A, A', B, B', and members a, a, and b, b; and comprises the channel iron D (consisting of web 40 d and parallel flanges d¹, d²), the channel iron E (consisting of web e and parallel flanges e¹, e²) and end members D¹, D¹.

End members D¹, D¹, are respectively provided with a flange, D², on which the ends 45 of web d of channel iron D, rest, and to which said web is rigidly secured by rivets D³, D³. Flange d¹ of channel iron D is rigidly secured to standards or legs B, B', by rivets d³, d³. The web e of channel iron E is rigidly secured to standards A, A¹, by rivets e³, e³. Flange e² of channel iron E, web d of channel iron D and plate E¹, are 50 rigidly secured together by rivets D⁴, D⁴.

55 E², E² (Figs. 2 and 3) represent adjustable members which are mounted on heads D¹,

D¹, and adjusted by means of bolts E³, E³, and secured in adjusted position by means of bolts E⁴, E⁴.

The upper jaw of the brake comprises 60 members F, G, and H. Member F is a channel iron having a central web (f), and flanges f¹, f². The web f is provided with a curving bend, as at f³, Fig. 3, extending the entire length of the web, so that the flange f² is in a horizontal plane. The portion 65 of the web f adjacent thereto is in a vertical plane and flange f¹ is in a vertical plane, with the portion of the web f which is between said flange f¹ and bend f³ in a 70 horizontal plane (see Fig. 3).

The members G, G, respectively consist of a head provided with a horizontal rib or flange g, and an inclined rib or flange g¹, and also provided with a fulcrum, G¹, which extends into a slot, G², in adjustable member E² on head D¹, at each end of the brake. The plate H and channel iron F are rigidly secured together by rivets h, h, said rivets 75 extending through the curved portion or bend f³ of web f. Heads G, G, are secured to the ends of channel iron F by rivets g², g², which extend through said web f and through the ribs g, g, and plate H is secured to ribs g¹, g¹, by rivets g³, g³, which 80 extend therethrough and through said plate. Plate H is bent the entire length thereof, as at h¹, adjacent to flange f², and the portion h² of said plate (extending from bend h¹ to the edge of the plate) rests on said flange 85 and is parallel thereto. I represents a steel plate on the under side of the horizontal flange of channel iron F, and i, i, represent 90 rivets which extend through said plate, through flange f² and part h² of plate H, 95 rigidly holding said parts together. The lower headed ends of rivets i, i, are embedded in plate I, and said plate is arranged to be forced down on to the sheet or bar 100 of metal which is to be bent or folded by the brake, to hold said sheet or bar firmly in place, by means of lever J, eccentric j, on pivot J¹, and link K. K¹ represents a pivot which is secured in head D¹, and on 105 which the lower end of link K is pivotally mounted. k represents a stop, to limit the movement of lever J in its travel from the position in which it is illustrated in Fig. 2 to the left, as viewed.

The bending leaf or apron of the brake 110 comprises the heads L, L, which are fulcrumed on pivots L¹, L¹, said pins being rig-

idly secured in heads D^1 , D^1 , plate M , which is secured to heads L , L , by rivets l , l , and the steel plate N which is curved at n , with the edge thereof adjacent to said curve secured to plate M by rivets m , m .

O , O , represent sockets on the sides of heads L , L , O^1 , O^1 , represent rods, and O^2 , O^2 , counter weights on said rods.

The construction of the upper jaw of the bending brake hereinbefore described is designed to give great rigidity to the forward edge of bar I when a plate, sheet or bar of metal (see X , Fig. 3), is bent or folded thereover, by the turning of the bending leaf on its fulcrums L^1 , L^1 , from the position in which it is illustrated into a plane parallel to, or at an acute angle to, plate H .

The purpose of making the bed of the brake of channel irons D and E and plate E^1 , joined by rivets D^4 , D^4 , extending through flange e^2 , web d , and said plate, as described, is to obtain an integral horizontal table (web d), extending from the forward flange d^2 to the back flange d^1 , thus obviating any liability of said bed giving or being bent in any direction when great pressure is brought to bear on said plate E^1 , by forcing of the upper jaw down on the material about to be bent and positioned between the jaws, and also, when great force is applied to said lower jaw in the bending of said material.

I claim;

1. In a bending brake, the combination of standards, heads and a bed, all rigidly secured together, said bed comprising channel irons, the central web of one thereof positioned in a vertical plane and its flanges in horizontal planes and the central web of the other positioned in a horizontal plane and its flanges in vertical planes, and a bar, the horizontal web of the second named channel iron resting on the upper horizontal flange of the first named channel iron, and one of the vertical flanges of said second named channel iron extending downward in front of the horizontal web of the first named channel iron, said channel irons and said bar all secured rigidly together and arranged to form the lower jaw of the brake with the central web of the second named channel iron forming the table of said bed.

2. In a bending brake, the combination of standards, heads and a bed, all rigidly se-

cured together, and an upper jaw adjustably mounted on said bed, said upper jaw comprising a channel iron having a longitudinally extending curved bend in the central web thereof, to position a portion of said web and one of its flanges in horizontal planes and a portion of said web and its remaining flange in vertical planes, in combination with a plate provided with a longitudinally extending bend to position a portion thereof in a horizontal plane arranged to rest on the upper face of said horizontally positioned flange, with the body of said plate which is adjacent to said curved portion of the web of said channel iron rigidly secured thereto, a plate on the under side of said horizontally positioned flange, said last named plate, the portion of said first named plate which rests on said flange, and said flange all secured rigidly together.

3. In a bending brake a bed, an upper jaw adjustably mounted on said bed and comprising a channel iron having a longitudinally extending curved bend in the central web thereof to position a portion of said web and one of said flanges in horizontal planes, a plate provided with a longitudinally extending bend to position a portion thereof in a horizontal plane arranged to rest on the upper face of said horizontally positioned flange, with the body of said plate which is adjacent to said curved portion of said web of said channel iron rigidly secured thereto, a plate on the under side of said horizontally positioned flange, said last named plate, the portion of said first named plate which rests on said flange and said flange all rigidly secured together, in combination with a lower jaw comprising channel irons and a metal plate, the central web of one of said channel irons positioned in a vertical plane with the upper flange thereof in a horizontal plane, and the central web of the other channel iron positioned in a horizontal plane and the forward flange thereof in a vertical plane, said upper horizontal flange, said horizontal web and said metal plate all secured rigidly together, with said forward vertical flange arranged to form the forward edge of said lower jaw.

NIC KRUMP.
